Samuel May, Providence, R. I.

Sitter Patent

The Schedule refers to another Sitter Patent and I shall copy the same containing a description of the same, but I may have left off the improvement called "Bray's Water Side Coal Burner".

It is known that I Samuel May, of Providence in the County of Providence and State of Rhode Island, have made a new and useful Improvement in the engine side, Called "New Water Side Coal Burner", which is described as follows:

The first modification of my improvement is in the burning of timber, &c. Call the main or furnace Pot or pot as I call it. It consists of a chamber through which the upper part of the pot rests, a pot or vessel to contain the fuel with a grate in front, the upper chamber through which the fuel is introduced, which the air is distributed through and above the furnace to be upon the top a certain water and the bottom part upon which the furnace is built or constructed is cast with an opening in its centre through which the water passes from the pot into the furnace, and to admit the furnace to burn timber, having its grate, its engine, cast with a side plate to admit the engine, and you don't have to go to admit the furnace, and the furnace is built with the round perforations or holes to connect it with the fuel chamber.

The pot or vessel to contain the fuel with a grate in front is made of cast iron and lined with clay, it is in the form of the lower chamber of a furnace, and the bottom of the pot, and pot, are required to be lined with clay, the bottom of the pot, and pot, are required to be lined with clay, the pot is cast on the other having holes in them, through which the steam goes to decompose the pot, or slate, so as to open an opening in it to receive the engine, made by the upper part of the red chamber, so fastened on the top of the pot chamber by iron, passing into the plate and over cast on the top of the pot or fuel chamber.

7893X

The gate is made and can be taken out to clean the pipe. The upper chamber there which the pipe is put into by which the Caloric is distributed evenly is formed by four plates of Cast iron properly jointed and mounted with Grecian devices and united together to the bottom plate by an incision down the top plate having an opening in it similar to that in the bottom plate to one of these plates is a flue passing through it made to receive a smoke pipe. The bars are to prevent coal getting into the pipe.

The ash pan is made of cast iron of a rectangular figure open at top having flangs which settle in the grooves in the under-side of the bottom plate. The Blower is a plate of Cast iron in shape like a spade with the opening in the side chamber for the gate and iron on top projection pointing cast in it in grooves or cavities left in the lower plate. When it is time to use it acts as a shovel to ignite the fuel by closing the opening in front of the gate and when burnt close it joins the hearth, over the opening in the bottom plate above the ash pan and which it is also made to fit. The ornamented table on the top to contain materials. Made of cast iron of a square figure either with or without a square plate to stand a jar over the body of the stove and can be removed at pleasure to admit fuel.

There are four bars cast out of Cast iron which slide in the holes made grooves in the under-side of the bottom plate.

The large or bottom stove is in principle the same as the before described Grecian stove. With this difference that instead of the iron chamber for distributing the heat as before described there is a. kitchen of a round hollow iron made of cast iron and placed over a kind of incision in the top plate of the side chamber for the fuel, this is made of Cast iron with plain yellow pat work, having a chamber for distributing the Caloric or heat communicated with gotten or smoke.

There are four pieces Cast iron Buttocked with which the four plates of the pat work at the four angles by means of iron rods passing through them on the top of them are four pinnacles fastened to the four sides and made hollow to receive the top of the top, the handles of the doors forming the caps or tops of the pinnacles, the the top is placed a square plate for closing up the top of the stove when the pinnacles mounted with ap-

appropriate other advice. The pipe is attached to the fire and a stopper
a sliding damper.

Operation. The water goes at top and flows down beneath
it being mixed a small quantity of bedding such as Shaving wood
shaken up with the pipe or small charcoal through the top pipe, this
to put the chimney cool. The bedding being lighter than air
will be carried up by gravity of the pipe, which increases the strength of air
and draws up the fire which ignites the combustible coal. When the coal
is sufficiently ignited the slide or damper is turned down and the
fire managed in the usual way.

The advantages arising from the above are
-and the means of constructing stoves for burning Anthracite Coal are
-first, Cheaply, by having the Chamber of Combustion lined with fire
clay, which the Coal is retained or distributed in the most econom-
-ical manner. Whilst the upper Chamber being of cast iron only suffer
the heat to pass quickly through it to the fire. Under the fire
-constructing or clay lining at the bottom of the Chamber operates
-the furnace to produce fire in a very small quantity of coals
-any and for a long time.

The invention here claimed and described
is to be found by Setons Patent Office in the peculiar construction of the
Anthracite Coal burns and their several parts as before described, and
particularly the lining of the Chamber of Combustion with fire clay to
-as retain or distribute the Coal to heat with the greatest economy
-and the manner of fitting the door or baffle to make part of the heat
when open or turned down.

To the further illustration of my invention
I refer to the model and drawings of the same deposited in the above
office. Direct Providence the 13 day of November 1833
